UNITED STATES PATENT OFFICE

HOMER L. ROGERS, OF CINCINNATI, OHIO, ASSIGNOR TO THE PHILIP CAREY MANUFACTURING COMPANY, A CORPORATION OF OHIO

SYSTEM OF THIRD RAIL INSTALLATION

Application filed June 27, 1928. Serial No. 288,720.

My invention relates to system of third rail installations.

My invention is particularly addressed to providing protective covers and insulating means for third rails or other electric conductors, a portion of which, by reason of their use, must be exposed so as to contact with a moving member, such as the shoe which contacts with the third rail conductor or a trolley wheel which conducts an overhead or underground trolley and similar conductors.

My invention is addressed to providing such conductors with a protective cover which insulates the greater portion of such conductors, protects the conductor from water and moisture, and likewise provides a cover, that will not absorb moisture, will not decay or deteriorate, under use. My system may be readily applied to the electric conductor on old as well as to new installations. Under my system the third rail covers will far outlast protective covers heretofore in use and will greatly prolong the life of the electric conductor.

While in the specification and the drawings I have shown my improved system and cover applied to a typical third rail in which the shoe on a moving vehicle contacts with the lower side of the rail, it will be readily understood that my cover may be applied to other conductors and that the form and shape of my cover depends upon the conductor to which it is to be applied.

In the drawings, Fig. 1 is a cross section of my system applied to a third rail. Figs. 2 and 3 are modifications of same.

In the drawings, A is the third rail to which is shown applied a cover composed of three members; the top member B encloses the top and side of the top ball of the rail and the two members CC enclose the underside of the top ball of the rail, the upper side of the lower ball of the rail, and contact with the web of the rail. D is a bituminous adhesive or cement which is applied to the portions of

the rail with which my cover comes in contact and is also applied between the adjacent members of the cover so as to provide adhesion for the parts of the cover to the rail and to each other, thereby forming a water tight joint between the respective members of the cover, and not only cementing the cover to the rail but providing a water tight seal between the cover and the rail so that moisture cannot penetrate between same.

As shown in Fig. 2, the members CC are slightly different in form so that the top member B extends down and overlaps the members CC. In Fig. 3 the cover is composed of but two members; B having integral with it a portion which projects against the web of the rail, and a second member C corresponding to the member C in Figs. 1 and 2, except, that the cross sectional form is somewhat modified. This modification of the section C in Fig. 3, as will be seen, provides for a straight uninterrupted surface provided by the outer exposed surface of the member B and the outer exposed surface of the member C. Of course, the member C could be of any form desired although I prefer that whatever form is used, the members C project beyond the side of the lower ball of the rail as shown in the drawings so that any dripping of rain will be to the ground and not on to the rail A, and I have for that reason provided that the lowest point of the members C be arranged some distance from the side of the lower ball of the rail so that as the moisture or rain drops, even though there is a strong wind or current of air being created by a passing vehicle the moisture or water will drop to the ground and not contact with the rail. If desired, of course, the lower portion of the member C adjacent the rail could extend down and contact for some little distance with the parallel vertical sides of the lower ball of the rail although this is not necessary.

I prefer to use a cover formed, as explained

in greater detail in my co-pending application Serial No. 288,721, filed June 27, 1928 from a mixture composed of bituminous material, preferably asphalt; fibrous material and a comparatively fine mineral material, either a powdered mineral or a fine granular mineral, mixed together while the bituminous material is heated to form a homogeneous mass. This mixture or homogeneous mass of bitumen is then, while in a heated condition, moulded or formed under pressure to the desired shape so that the cover will conform to the contour of the surface to which it is to be applied. This moulding or forming is under sufficient pressure to compact the mass with the result that when it has cooled the cover will be a comparatively rigid board-like, yet plastic, preformed cover that is readily workable, is comparatively easy to cut, will not crack or spall, is waterproof, into which nails may be readily driven, and will maintain its preformed shape under ordinary handling, while being worked and in use. If desired, to prevent adhesion of covers or parts of covers in shipment or storage, one or more of the surfaces of the cover may be coated with a suitable powdered material, such as soap-stone, talc or other powdered mineral, or the same may have applied to it a film of non-adhesive material which can be readily removed by water or a suitable solvent so that the cover or separate members of the cover may be brought into adhesive contact with the rail and at their adjacent surfaces with each other. If desired, the members of the cover may be attached together by staples E as shown in Fig. 1 or by nails or spikes F, shown in Figs. 2 and 3, in conjunction with the adhesive cement D. If desired, the cement may be dispensed with and the nails, spikes or staples used alone, or the nails, spikes or staples may be used, without the adhesive D.

If desired, the cover could be made of two parts separated in the center of the top portion, for instance, in Fig. 3 the two members would be formed so that one member would be to the right of an imaginary vertical line through the top of the cover of Fig. 3 and the other would be a similar portion on the left of such line. In the event of such a cover being formed a tongue and groove could be provided in the adjacent parts if desired and then the parts could be cemented together after being placed on the rail or the tongue and groove could be dispensed with and merely straight sides provided which could be cemented together. My cover may be provided in any suitable lengths although lengths from 3 to 5 feet are probably preferable as a matter of convenience in handling. When applied the adjacent ends of the cover are preferably cemented by suitable adhesive cement and may be stapled together by staples similar to those shown in Fig. 1, or if de-

sired, the adjacent ends could be provided, the end of one section with a tongue and the end of the next adjacent section with a groove so as to break the joint where they were brought together, in this way assisting in obviating the possibility of moisture passing between adjacent sections of the cover. 70

I have not shown in the drawings the means for supporting the third rail, as any of the ordinary means may be used and the cover by reason of its ease of workability can be fitted about the rail support. 75

Claims:

1. A third rail system comprising a third rail, a cover for same, composed of a body 80 of material containing bitumen, preformed to conform to the contour of the rail and means attaching said cover adhesively to the rail.

2. A third rail system comprising an electric conductor, a cover for same each section of which is composed of a plurality of parts adapted when assembled to conform to the contour of, and cover, the conductor except a longitudinal contact portion thereof and 90 adhesive means for uniting the parts of said cover together and to the conductor.

3. An electric conducting system composed of an electric conductor, a cover for same consisting of a plurality of members 95 preformed from a material containing bitumen and fibres to conform to the contour of the greater portion of the conductor, and metallic clamping means uniting adjacent contacting surfaces of the cover members, the bitumen and fibers in said members being in such proportions that such sections are penetrable by said clamping means without fracture. 100

4. An electric conducting system composed of an electric conductor, a cover for same consisting of a plurality of members preformed from a material containing bitumen and fibres to conform to the contour of the greater portion of the conductor, and a 110 non-electrical conducting cement affixing said cover to the conductor.

5. An electric conducting system comprising a conductor, a cover for said conductor composed of a plurality of parts adapted when assembled to form a cover conforming to the contour of the conductor and to contact with the surface of same, and means for holding said cover members in operative relation with respect to said conductor, said means consisting of a cement, cementing said cover members to the conductor. 115

6. An electric conducting system comprising an electric conductor, a cover for same consisting of a plurality of members, containing bituminous and fibrous materials, preformed so that when assembled they conform to the contour of a portion of the conductor and means sealing the joints between adjacent contacting surfaces of the cover 120 130

members when in position on the rail, and a non electrical conducting cement, cementing the cover on the conductor.

7. A third rail system comprising an electric conducting third rail of dumb-bell cross-section, a cover for said rail formed of water impervious, electrically non-conducting material, said cover comprising a preformed portion conforming to the contour of and in contact with a longitudinal side portion of the rail, a separate preformed portion conforming to the contour of and in contact with the top and sides of the top portion of the rail and means for connecting said portions together when in position on the rail.

8. A third rail system comprising an electric conducting third rail, a cover for said rail formed of water-impervious electrically non-conducting material said cover comprising a preformed portion conforming to the contour of and in contact with a longitudinal side portion of the rail, a separate preformed portion conforming to the contour of and in contact with the top and sides of the top portion of the rail, a separate preformed portion corresponding to the first mentioned portion in contact with the opposite side of the rail and means for connecting said portions together when in position on the rail.

9. A third rail system comprising an electric conducting third rail, a cover for said rail provided with a portion conforming to the contour of and in contact with a longitudinal side portion of the rail, and a portion conforming to the contour of and in contact with the top and sides of the top portion of the rail, and means cementing said cover to the rail.

10. An electric conducting system comprising an electric conductor of dumb-bell cross-section, an insulating cover for said conductor adapted to contact with substantially the entire upper and central parts of the conductor, said cover being preformed in separate top and side sections of water-impervious and electrically non-conducting material, the top section being adapted to extend across the top and downwardly over both sides of the upper part of the conductor, the side sections being adapted to extend over the central part of the conductor and also contact with the top section whereby said sections may be assembled on the conductor and means for securing said top and side sections together.

11. An electric conducting system as in claim 10 in which the downward extensions of the top section overlap the side sections, and fastening means are passed through the overlapping portions of the top section into the side sections to hold the latter in position.

12. An electric conducting system as in claim 10 in which the sections of the cover are formed of a bituminous material and a

filler in such proportions that such sections are penetrable by nails without fracture and the sections are secured together by nails.

13. An electric conducting system as in claim 10 in which the sections of the cover are formed of bituminous material and are united to each other and adhesively attached to the conductor by cement comprising bituminous material.

In testimony whereof, I have signed my name to this specification.
